UNITED STATES PATENT OFFICE.

JOHN W. BAER, OF DANVERS, MASSACHUSETTS, ASSIGNOR, BY MESNE ASSIGNMENTS, TO UNITED SHOE MACHINERY CORPORATION, OF PATERSON, NEW JERSEY, A CORPORATION OF NEW JERSEY.

FORM-HOLDING MEANS FOR SOLE-PRESSING MACHINES.

1,300,549.

Specification of Letters Patent. Patented Apr. 15, 1919.

Application filed February 12, 1914. Serial 818,243.

To all whom it may concern:

Be it known that I, JOHN W. BAER, a citizen of the United States, residing at Danvers, in the county of Essex and State 5 of Massachusetts, have invented certain new and useful Improvements in Form-Holding Means for Sole-Pressing Machines; and I do hereby declare the following to be a full, clear, and exact description of the invention, 10 such as will enable others skilled in the art to which it appertains to make and use the same.

The invention relates to form holding devices for sole pressing or sole leveling ma- 15 chines.

The object of the invention is to provide novel and improved means for positioning and securing the form upon its carrier which will enable the adjustments requisite to the 20 accurate positioning of the form to be quickly and conveniently made, and which will firmly secure the form to the carrier while permitting it to be readily removed and replaced. To these ends the invention 25 consists in the features of construction and combinations of parts hereinafter described and referred to in the claims, the advantages of which will be obvious to those skilled in the art from the following detailed descrip- 30 tion of the embodiment of the invention shown in the drawings.

In the drawings, Figure 1 is a side elevation of a form carrier and form embodying the invention in its preferred form; 35 Fig. 2 is an end elevation looking toward the left in Fig. 1; Fig. 3 is a vertical sectional view on line 3—3, Fig. 1; Fig. 4 is a plan view; and Fig. 5 is a plan view of the form detached from its carrier.

40 In the drawings the invention is shown as embodied in a form carrier and form adapted for use in sole pressing machines of the type shown and described in the patent to Mayo, No. 861,746, June 30, 1907, 45 in which the sole of a shoe is subjected to a rolling pressure between the last upon which the shoe is supported and a coöperating sole pressing form. As shown, the form 2 is removably supported on a carrier 4 formed 50 on the lower end of a plunger 6 by which the carrier is mounted on the swinging carrier-arm of the machine in the usual manner. The devices for positioning and securing the form on the carrier are constructed

and arranged to secure the various adjust- 55 ments requisite for accurately positioning the form to coöperate properly with the shoe supporting last, and in order that the adjustments more frequently required may be accurately and quickly made, the position- 60 ing devices for securing these adjustments are so arranged that they are accessible while the form is supported on the carrier. By manipulation of the positioning and securing devices, the form may be ad- 65 justed with relation to the carrier either longitudinally or laterally, may be tilted either longitudinally or laterally, or may be swung laterally to bring its medial line into line with the medial line of the last. The 70 form may therefore be accurately positioned to coöperate properly and efficiently with the last in pressing and shaping the shoe sole.

In the construction shown the form is 75 secured to the carrier by four clamping and positioning bolts 8, 10, 12 and 14 mounted on the carrier in position to engage oppo- 80 site sides of a longitudinal rib 16 projecting from the upper side of the form. One or 85 both sides of the rib are inclined inwardly to provide inclined surfaces for engage- 90 ment with the securing bolts, so that the bolts will tend to draw the form toward the carrier when they are forced against the 85

opposite sides of the rib. The vertical position of the form with relation to the under side of the carrier is determined by four 95 positioning stop bolts 18 which are screwed into the upper side of the form, and are ar- 100 ranged to engage the under side of the carrier on opposite sides of the rib 16 and of the medial line of the form. When the clamping bolts are tightened, the heads of the stop bolts 18 are drawn firmly against the under face of the carrier, and determine the position of the face of the form with relation to the carrier. By adjustment of the stop bolts 18 the face of the form may be brought toward or from the carrier, or the lateral or longitudinal tilt of the form may be varied to bring the face of the form into proper relation to the coöperating last. The adjustment of the bolts in positioning the face of the form may be effected while the form is supported on the carrier, so that the operator may observe the relation of the form to the last, and make the requisite ad- 105

justments rapidly and accurately. By manipulation of the securing bolts 8, 10, 12 and 14, the form may be adjusted laterally, or may be swung laterally to bring the medial line of the form into proper relation to the medial line of the last. These adjustments may also be made while the form is in position on the carrier, so that it may be brought into coöperating relation with the last in making the adjustments. The longitudinal position of the form is determined by a positioning stop bolt 20 which is screwed into the rear end of the rib 16 and engages a stop formed by the rear end 22 of a dove-tailed groove 24 which is formed in the under side of the carrier to receive the rib.

The opposed faces of the rib 16 which are engaged by the opposed bolts 8 and 10 and the opposed bolts 12 and 14, may be inwardly inclined to coöperate with the bolts in drawing the form firmly against the under side of the carrier. It is preferred, however, to provide vertical bearing surfaces 26 on one side of the rib to coöperate with the bolts 10 and 14 at that side in positioning the form laterally. With this construction the bolts 10 and 14 may be adjusted to properly position the form laterally, and the bolts 8 and 12 be manipulated in securing and releasing the form. The ends of the bolts 10 and 14 will coöperate with the vertical surfaces 26 to maintain the form in position as it is drawn toward the carrier by the tightening of the bolts 8 and 12. In order that the form may be readily withdrawn from the carrier when the bolts 8 and 12 are loosened, the side of the rib 16 is under cut at 28, as indicated by dotted lines in Fig. 5 to pass longitudinally over the ends of the bolts 10 and 14.

In order that the carrier may be used to support forms provided with the securing and positioning screws indicated in Fig. 1 of the patent to Mayo above referred to, the carrier may be provided at its rear end with a grooved plate 30, and a second grooved plate indicated in dotted lines at 32 in Fig. 1 may be temporarily secured on the front end of the carrier by the bolts 34. The plates correspond to the plates on the form carrier which are engaged by the screws on the form indicated in Fig. 1 of the Mayo patent.

While it is preferred to employ the specific construction and arrangement of parts shown and described, it will be understood that this construction and arrangement is not essential to the broader features of the invention, and may be varied and modified as found desirable or best suited to the machine in which the invention is to be embodied.

Having explained the nature and object of the invention, and specifically described one

form of mechanism in which it may be embodied, what is claimed is:

1. Form holding means for sole pressing machines having, in combination, a form carrier, a form, a longitudinal rib on one of said parts, and two sets of opposed securing bolts on the other part engaging opposite sides of the rib and spaced longitudinally a sufficient distance to secure an angular adjustment of the form relative to the carrier when the securing bolts are relatively adjusted. 70

2. Form holding means for sole pressing machines, having, in combination, a form carrier, a form, adjustable positioning devices on one of the members engaging the other and arranged to vary the lateral or longitudinal tilt of the form, and adjustable securing devices for securing the form to the form carrier arranged to vary the lateral adjustment of the form. 80

3. Form holding means for sole pressing machines, having, in combination, a form carrier, a form, an adjustable positioning device for determining the longitudinal position of the form on the carrier, and adjustable positioning devices accessible when the form is on the carrier for determining the vertical position of the form with relation to the carrier. 90

4. Form holding means for sole pressing machines, having, in combination, a form carrier, a form, adjustable stop bolts on one of the members engaging the other to position the form vertically, a longitudinal rib on the upper side of the form, and laterally-adjustable securing devices on the carrier for engaging opposite sides of the rib. 100

5. Form holding means for sole pressing machines, having, in combination, a form carrier, two sets of opposed securing bolts on the carrier, a form, and a rib on the upper side of the form having opposed bolt engaging surfaces corresponding to each set of bolts, one at least of which is inclined inward toward the base of the rib. 105

6. Form holding means for sole pressing machines, having, in combination, a form carrier, a form, adjustable positioning devices accessible when the form is on the carrier arranged to vary the longitudinal or lateral tilt of the form, a rib on the form and clamping devices on the carrier engaging the rib. 115

7. Form holding means for sole pressing machines, having, in combination, a form carrier, two sets of opposed securing bolts on the carrier, a form provided with a rib on its upper side adapted to be engaged by the bolts, and positioning bolts on the upper side of the form for engaging the under side of the carrier. 120

8. Form holding means for sole pressing machines, having, in combination, a form carrier provided with securing bolts, 130

a form provided with a rib adapted to be engaged by the bolts, positioning bolts on the upper side of the form arranged to engage the under side of the carrier, a longitudinal 5 stop bolt on the form, and a coöperating stop on the carrier.

9. Form holding means for sole pressing machines, having, in combination, a form carrier, a longitudinal groove in the 10 under side of the carrier, securing bolts projecting into the groove from opposite sides,

a form provided with a rib to enter the groove, one side of which is inclined inward, a stop bolt in the end of the rib arranged to engage the end of the groove in 15 the carrier, and positioning stop bolts on opposite sides of the rib arranged to engage the under side of the carrier.
